UNITED STATES PATENT OFFICE.

WILLIAM H. PRIESS, OF BELMONT, MASSACHUSETTS, ASSIGNOR TO WIRELESS SPECIALTY APPARATUS COMPANY, OF BOSTON, MASSACHUSETTS, A CORPORATION OF NEW YORK.

RADIOTRANSMITTER.

Application filed August 31, 1922. Serial No. 585,464.

This invention relates to improvements in radio transmitters, particularly radio transmitters of the quenched spark type and of the arc, tube and alternator types for continuous wave transmission.

In this invention, while the several tuning or variable elements necessary to change the wave length or for switching from sending to receiving positions and vice versa may be locally controlled directly at the transmitter, yet the invention is more particularly adapted for the more or less remote control of such elements; that is, for controlling their adjustment from a distant point which may be a few feet, several miles or even hundreds of miles from the transmitter.

At the present time, the circuits of radio transmitters are altered by manually shifting switches or clips connected mechanically to the circuits. It is desirable to control from some more or less distant point the wave length of the transmitter and in addition to control certain other radio frequency connections such as the antenna or aerial and its connection to ground, and also to control certain circuits such as the main power circuit and the 500 cycle circuit (if one is present) and the auxiliary circuits, such as the key and generator field circuits. At present, practically the only circuit controlled at a distance is the key circuit, and this control consists simply in lengthening the relay key line, determined by the separation of transmitter and operating location.

The advantages of a distant control for the operating circuits and for changing the wave lengths are numerous. For example, a chain of transmitting stations located in desirable geographical positions can be operated from one central point. When such operation is attempted at the present time, instructions must be given the attendants at the transmitter location when changes in wave length are desired. Such instructions are given by telephone. This offers a distinct hindrance to the speed of transmission and requires an increased maintenance force at the transmitter stations. An important advantage is secured, even when the transmitter is only separated a short distance from the operator, when a full control of the wave lengths and operating circuits is made possible at the operating location, since the various circuits can be easily and

rapidly shifted without the operator leaving his table. Furthermore, the use of a remotely distant control permitted by this invention decreases the cost of radio communication by permitting a station to handle more business in a given time. Still another advantage of the invention is that the high tension antenna lead at the transmitter is at a point remote from the operator and consequently frees him from the danger of accidental contact with the lead.

The apparatus used in the present invention for shifting the wave lengths and for controlling the power circuits and shifting from the sending to receiving positions and vice versa comprises an electromagnetically operated instrumentality or instrumentalities at the transmitter for directly operating the various adjustable and tuning elements, a controlling device or devices at the more or less distant point under the control of the operator, and an electric line or lines linking the instrumentalities at the transmitter with the operator's control device.

For shorter distances, it is preferable to provide separate circuits connecting each instrumentality with the control device. However, in cases where the transmitter and operating location are separated long distances,—for example, several miles or even hundreds of miles,—it is preferable, and even necessary, to operate and control the transmitter from the distant location over as few wires as possible connecting the points, from the considerations of installation and maintenance costs of such long lines.

With a single pair of wires for the longer distances, the instrumentalities at the transmitter may be actuated to make the adjustments by having the control device at the remote position control various types of current each of which would actuate sensitive relays controlling the various adjustments of the transmitter. For instance, at the operator's position, I provide a source of direct current and a source of alternating current. Near the transmitter end and interposed in the circuit between it and the operator are located two polarized relays, one operated only by the direct current in one direction and the other operated only by the direct current in the opposite direction. These relays operate the key and the send-receive switch. A third non-polarized relay is then

provided near the transmitter, which is sensitive to alternating current only and is connected in series with a large condenser across or bridging the line. The third relay would have a suitable time constant so as to be insensitive to the pulses which actuate the other relays. By the use of synchronized selector systems at the operating and transmitting ends of the line controlled from the operator's end via the alternating current relay, the circuits at the transmitter controlling the various wave-length settings can be controlled.

This method employed for long distances may be slightly varied. For instance, the polarized relays operated by direct current may control a wave changer release mechanism and a wave changer selector. Circuits including each wire and ground may be utilized to operate the start and stop mechanism or the send-receive mechanism, while the bridge line operated by alternating current may be used to control the key. The wave-length changing mechanism operated will depend on the number of direct current impulses caused by the operator. Each time a pulse is transmitted, a damped time element switch is actuated through a magnetic ratchet. The time switch will ultimately close one wave-length changing mechanism or another, depending on the number of impulses received by it.

The local wave-length adjusting or changing mechanism, which can be controlled from a distance by any suitable control device and line (depending, of course, on its length), varies or adjusts such parts of the high frequency circuits as will produce the desired wave length—for instance, as here illustrated, the primary coil, the coupling coil and the antenna inductances or load coils. The adjustments for different wave lengths may be accomplished by motors or by other electromagnetic devices or solenoids which actuate different switches for throwing in the required capacity and inductance for each desired wave length.

As herein illustrated, I provide a separate electromagnetic device or solenoid for each wave length except the longest, the transmitter being tuned to the longest wave length when all the wave changer solenoids are in inactive or inoperative position. A similar solenoid is utilized for controlling the send-receive connections and the power and generator circuits. All of the wave changing solenoids must be in inactive position before any of them can be actuated to secure a desired wave length adjustment. This local mechanism can be controlled for a distance by any suitable selector or operating device over two or more wires as above outlined or in the manner herein illustrated and described as an embodiment of the invention.

An object of the invention is to provide a wave length changing control which is speedy and efficient.

Another object of the invention is to provide, in connection with a transmitter, means for controlling it from a distance.

A few of the features (among others) of this invention are as follows:

(1) The provision of a separate actuating device for each wave-length setting to throw in the proper value of primary inductance, coupling inductance and antenna inductance for each wave length setting desired.

(2) Means for switching from sending to receiving by connecting the antenna to the transmitter and receiver alternately, grounding the receiver when the apparatus is sending.

(3) Means ensuring the opening of all astuating devices before a new wave length setting is made.

(4) The provision of a short circuiting clip between the secondary of the transformer and the antenna inductances or coils for preventing undue rise of potential in the high frequency circuits, which would happen if the antenna coils remained open circuited, this clip setting the transmitter for the longest wave length when the other wave length changing devices are open or in inoperative position.

(5) The provision of electromagnetic spring controlled devices for changing wave lengths and for changing from sending to receiving and vice versa.

(6) The provision of circuits which energize the controlling devices only when they are operated or during the time of useful work.

(7) The provision of a distant control device which, when moved to close a contact for a different wave-length setting, first releases any electromagnetic wave-changing device which may be in operative position.

(8) Apparatus in which high potentials are removed from the operator's table.

(9) A minimum number of switches for each wave length adjustment, one in the primary circuit and one in the secondary circuit, the secondary switch blade being directly connected to a variable tapping point on the secondary coil.

(10) The longest wave length is produced by opening all the wave changer switches, thus reducing the number of wave changers necessary. The circuits are also always tuned. If the operator actuates the wave changer while the key is depressed, no harmful effect is produced, because of this tuning, preventing an undesired rise of potential.

(11) Variometer arrangement of loading coils to permit the use of a fixed short circuit lead for the longest wave length and to

provide for a variometer adjustment for the longest wave length.

(12) The location of a series antenna condenser, used on the shortest wave length, in the lead between the secondary coil and the switch for this wave length adjustment.

(13) The mounting for the load coils.

In the accompanying drawings, I have illustrated an application of the invention to a quenched spark transmitter in which:

Figure 1 is a diagram of the various circuits of the transmitter and control devices;

Fig. 2 is a front elevation of the transmitter and controls;

Fig. 3 is a side view thereof;

Figs. 4 and 5 are detail views of the switch controls for the generator circuits;

Fig. 6 is a sectional elevation of an electromagnetic control device;

Fig. 7 is an end view thereof;

Fig. 8 is a plan view thereof;

Fig. 9 is a plan view of the control box; and

Fig. 10 is a sectional view thereof.

In Fig. 1 is illustrated diagrammatically the transmitter radio frequency circuits, the electromagnetic devices for varying or shifting the wave lengths and the circuits controlling the electromagnetic devices. The transmitter illustrated is of the quenched spark type and comprises a primary circuit P having in series therewith a spark gap SG, primary transformer coil PC and transmitting condensers C. The primary coil PC is inductively and adjustably coupled by coupling K to the secondary coil SC grounded at G. Interposed between the secondary coil SC and the antenna or aerial A are the inductances or loading coils L which are of the pancake type and are arranged as more fully described hereinafter. The load coils L are electrically connected at their outer end to the inner end of the secondary coil SC by means of a short-circuiting connection or clip Y while the opposite end of the inductances L is connected to aerial A by a conductor X. In the embodiment here illustrated, the apparatus can be adjusted for four wave lengths; for instance, for wave lengths of 300, 600, 800 and 1800 meters. The transmitter is normally tuned for the 1800 meter adjustment, when all of the electromagnetic control devices for the shorter wave lengths are in inoperative position.

The electromagnetic controls or devices for the shorter wave lengths are shown at I, II and III. Each of these magnetic devices cuts in such portions of the primary coil inductance, of the secondary coupling coil inductance and of the loading coil inductances as to tune the apparatus to the wave length desired. In the diagram (Fig. 1), the transmitter is set for the No. II wave length adjustment.

Electromagnetic device I adjusts the ap-

paratus for the shortest wave-length through a contact 1 which is connected by a conductor 2 to the variometer of the left-hand loading coil 3 of inductance L. The actuating arm 4 of the electromagnetic device I has a knife blade contact 4^a on its end connected to a conductor 5 which is clipped at its opposite end to the secondary coil SC at a point giving the required value of secondary coil inductance for this wave-length. In the conductor 2 is the series antenna or shortening condenser 6. Associated with the device I are the relatively movable contacts 7 and 8, the contact 8 being connected by a conductor 9 to the primary coil PC at a point to give the right value of inductance for this wave length adjustment and the contact 7 being mounted on the actuating arm of the electromagnetic device I and adapted to engage contact 8 when the arm is actuated. A conductor 10 connects contact 7 to the circuit P at a point 10^x located between the condensers C and the coil PC. When the device I is actuated (assuming that all devices I, II, III are in inoperative position), the contacts 4^a and 1 engage, connecting the coil 3 to the coil SC at a desired point through conductor 5, and the contacts 7 and 8 engage, placing the required amount of primary coil PC inductance in the circuit P. Thus when the electromagnetic device I is actuated, the required amount of primary coil inductance, secondary coil inductance and loading coil inductance are placed in circuit for this wave length, the use of two switches only being required, one controlling the primary coil inductance and the other controlling the secondary coil and loading inductances. The condenser 6 is also placed in circuit for this shortest wave length adjustment upon actuation of device I. When device I is actuated, the primary circuit P is completed through contacts 7 and 8, conductor 9, coil PC, gap SG, condenser C and conductor 10. The secondary circuit is completed through coil SC, conductor 5, contacts 4^a, 1, condenser 6, coil 3, conductor X and aerial A. In like manner, the electromagnetic devices II and III may be actuated to throw in corresponding values of primary and secondary coupling inductances and the required amount of loading coil inductance. For this purpose, there are provided the fixed or stationary contacts 1^a and 1^b, the connections 2^a and 2^b therefrom to the required points on the loading coils 3^a and 3^b, and the movable contacts 4^b, 4^c, co-acting with contacts 1^a and 1^b and connected by conductors 5^a and 5^b to the required points on the secondary coil SC. The devices II, III also control relatively movable contacts 7^a, 8^a and 7^b, 8^b connected by conductors 9^a, 9^b to the necessary points on the primary inductance PC and by conductors 10^a, 10^b to the point 10^x.

The electromagnetic device IV controls the send-receive positions of the device and alternately connects the aerial A to the transmitter and receiver. For this purpose, the 5 movable arm 11 of device IV is provided at one end with a contact 12 which is electrically connected permanently to the aerial A, and which, when moved or actuated, shifts the aerial connection from the sending position contact 13, which is in circuit with the transmitter, to the receiving position contact 14 which connects the aerial to the receiving apparatus (not illustrated) and is in spaced relation to contact 13. When the 10 arm 11 is in the position shown (the transmitting position), the receiver is grounded at 15 and is disconnected from the aerial, but when the arm 11 and contact 12 are shifted to engage the receiving contact 14, this 15 ground is disconnected. The magnetic device IV also controls certain other circuits (not illustrated) through the switches 16, 17, 18 and 19 (illustrated in detail in Figs. 4 and 5). The contacts 16 are in series with and, 20 control the main line of the 500-cycle generator. The contacts 17 are in series with and control the generator field and relay key. The contacts 18 control automatic starting and stopping devices (not illustrated). The 25 contacts 19 control a discharging resistance in the generator field circuit. Across the contacts 17 may be placed an arcing condenser. A switch on the panel permits the short-circuiting of contacts 18; that is, permits the continuous running of the motor generator independent of the send-receive switch. The discharge resistance used is the relay key resistance unit (not illustrated). This resistance unit is thrown 30 across the field slightly ahead of the time that the field and relay circuits are opened. The arcing condenser functions to break a comparatively low voltage arc as distinguished from the high voltage arc that would have been developed if the discharging resistance had not been thrown across the field.

When the apparatus is in the position illustrated in Fig. 1, it is transmitting and the contacts 16, 17 and 18 are closed, power being supplied from the generator to the circuit P across the transformer T in the usual manner. When it is desired to receive, the device IV is actuated in the reverse direction, the plunger 11^a upon arm 11 opening contacts 16, 17 and 18 and closing contacts or switch 19, and the aerial being transferred to the receiver contact 14 and disconnected from the transmitter. This movement also disconnects ground 15. The details of a practical embodiment of switches 16-19 and plunger 20 and their arrangements will be described more fully in connection with a description of Figs. 4 and 5.

In Figs. 2 and 3 is illustrated a practical

embodiment of the transmitter assembly and circuits illustrated in Fig. 1. The transmitter as here illustrated comprises a suitable channel iron supporting frame 20, to the front (Fig. 2) of which are secured 70 three insulating panels 21, 22 and 23. The panels and frame 20 support the aerial lead, the wavechanger, series antenna condenser, quenched gap, primary condenser, transformer, meters, starter switches and motor 75 generator controls. On the front of the lower panel 21 (Fig. 2) is mounted a double pole, double throw, fused main line switch 24 connected to either the ship line 25 or to a line 26 to a battery source of power. 80 Below switch 24 is mounted the starter or contactor mechanism 27 for the starting and deaccelerating device (not illustrated in detail). To the right of the starter 27 is a double-pole fused switch 28 for controlling the 500-cycle line. To the left of the starter 27 is a single pole switch 29 for controlling the circuits of the magnetic control devices. Switch 30 controls the generator field and 85 relay key circuits. 90

The starter 27 may be of any desired type, and inasmuch as it does not constitute part of the present invention, it is not more fully illustrated. Such starter, for instance, may consist of a main contactor, two stepwise contactors and a resistance can. The main contactor on starting closes the motor circuits through the resistance, and the stepwise contactors successively close as the motor comes up to speed, cutting out successively resistance in the resistance can. On stopping, the main and auxiliary contactors open and the counter E. M. F. of the motor causes the main contactor to close the circuit, which throws the resistance across the motor armature, providing a dynamic break for deaccelerating the motor. 95 100

Directly on the back of the lower panel (Fig. 3) is mounted the transformer T, which is enclosed in a box 31 and is not described in detail, as it may comprise any well-known type of transformer designed according to the requirements of the transmitter. This transformer connects the low frequency circuits with the high frequency 115 spark gap circuit. 110

Mounted above the transformer is the series antenna condenser 6, which may comprise any well-known type of condenser adapted for series antenna use. The wave-changer devices I, II, III and the send-receive operating device IV are mounted upon the front of the center panel 22 as illustrated in Fig. 2. Upon panel 22 is mounted the relay key 32, the motor field rheostat 33, the generator field rheostat 34 and the spark-gap SG. 120 125

The wave-changers are mounted between the front middle panel 22 and a rear insulating panel 36 (Fig. 2) spaced and connected 130

by four heavy bakelite dielecto tubes 37. The front panel 22 is bolted to the angle iron frame 20 and the rear panel 36 is bolted to and braced by metal struts 38, which are in turn bolted to the base of the angle iron frame 20.

The fixed primary coil PC is clamped to the four bakelite tubes 37 between panels 22 and 36. The coupling or secondary coil SC 10 is movably mounted directly behind the primary coil PC (Fig. 3) upon a bakelite tube 39, which is mounted for longitudinal movement axially of the coil PC to move coil SC towards and away from coil PC to vary 15 the coupling, the tube 39 being mechanically connected to a coupling adjustment handle 40 (Fig. 2) mounted at the front on panel 22. The means for adjusting the coils PC and SC relative to each other is not illustrated in 20 detail, as such means may be of any desired character whereby the separation between the coils may be varied or adjusted. Mounted transversely of the tube 39 and secured to move therewith is a terminal board 41 25 (Fig. 3). This terminal board is provided with four terminals 42 having leads 42^a therefrom terminating in clips 43 connected to the coupling coil SC at different points for cutting in different inductance for the several 30 wave-length adjustments in the manner illustrated diagrammatically in Fig. 1. One end of the coupling coil SC is connected to a radiation ammeter, the connection being 43.

The transmitting condensers C are mounted 35 in a rack in front of the primary coil PC and are fastened to the bottom bakelite rods 37. These transmitting condensers C may be of any desired type suitable for this purpose.

40 The four terminal blades 1, 1^a, 1^b, 13, are mounted upon the rear panel 36 (one of which 1^b is shown in Fig. 2). These blades or contacts 1, 1^a, 1^b, 13, which were described in connection with Fig. 1, are 45 arranged transversely in spaced relation across the upper portion of the inner side of the panel 36. The blade 13 (not seen in Fig. 2) is connected by conductor X to the end of the lowest or first loading coil 3. 50 The blade 1 (not seen in Fig. 2) is connected by conductor Z to the variometer of the first antenna coil 3. The blade 1^a (not seen) is connected by conductor 2^b to the variometer of the second antenna coil 3^a. The contact or blade 1^b is connected by conductor 2^b to the variometer of the third antenna coil 3^b. A series of terminals 44, four in number, corresponding to the number of blades 13, 1, 1^a, 1^b, are mounted in a line below 55 such blades upon the inner side of the rear panel 36. The more remote terminal 44, not seen in Fig. 3, is connected to a lead 45 from the series antenna condenser 6. Flexible leads 46 connect the movable contacts 4^a, 4^b, 60 65 4^c, with terminals 44 (not shown in Fig. 2),

while the short-circuiting clip Y is shown connected to terminal 44 shown in Fig. 3. Directly below the remote terminal 44 is a terminal 44^a having a connection 45^a to the other side of the series antenna condenser 6, 70 and having a flexible lead 44^b to a corresponding terminal on the coupling coil terminal block 41. When the shortest wavelength device is in position with the contacts 4^a and 1 engaging, the second stud 44^a of the system is connected through the series antenna condenser 6 to the coupling coil SC. A short-circuiting clip (not illustrated) may be provided to cut out the series antenna condenser in cases where very short antennæ 80 are employed. Flexible leads 47 connect three of the terminals 44 with the terminals on block 41, while the fourth terminal 44 (the more remote looking at Fig. 2) is connected indirectly to the terminal block 41 85 through terminal stud 44^a. A bracket 1 is mounted on the transmitter frame 20 and is provided with a binding post A¹ which is connected to the aerial A. The flexible lead A² is connected on one end to the post and at 90 the lower end to movable contact 12 (Fig. 1), whereby the aerial may be alternately connected to contacts 13 and 14.

In Figs. 6, 7 and 8, I have illustrated the details of construction of the electromagnetic actuating or control devices I, II, III, IV, for the various wave-length adjustments and send-receive switch. The transmitter of this invention has an independent contactor system for each wave-length adjustment except that for the longest wave-length. The several electromagnetic local operating devices are controlled manually from a distant point by a single handle. The local control devices comprise bakelite rods 4 and 11, illustrated diagrammatically in Fig. 1 and structurally in Fig. 3, which slide through and are supported upon bakelite guide pieces 60 and 61 (Fig. 3) supported by the upper members 37. To the rear ends of the rods 4 and 11 are secured the clip contacts 12, 4^a, 4^b, 4^c, adapted to engage the contacts 13, 1, 1^a, 1^b, when the rods are moved towards the rear as described above. The closing of these contacts (except contacts 12 and 13), throws into circuit a predetermined value of aerial inductance L and a predetermined value of the coupling coil SC. 100 105 110 115

The opposite ends of rods 4 and 11 have slots 62 in which the electromagnetic devices are pivoted. Each rod 4 or 11 is actuated as follows. An arm 63 is pivoted between its ends to a projecting bracket 64 on the electromagnetic device casing 65. The upper end of each arm 63 is provided at 120 125 66 to the rods 4 or 11 within slot 62.

Each arm 63 comprises an upper metal part 67 and a lower metal part 68 connected rigidly by a part 69 of insulating material, whereby the circuits are thoroughly insu- 130

lated from each other. The parts 67 of the wave changer devices form the contacts 7, 7^a, 7^b described above and illustrated in Fig. 1. A rearward movement of any wave 5 changer arm 63 moves a rod 4 rearwardly to close the contacts connecting the coil SC and inductances L. The primary circuit P (Fig. 1) is simultaneously varied in the following manner: The metal parts 67 (contacts 7, 7^a, 7^b) of the arms 63 are connected to the high potential stud 70 of the primary condenser system C by leads 71, corresponding to the leads 10, 10^a 10^b illustrated diagrammatically in Fig. 1, and are arranged to 10 engage the contact clips 8, 8^a, 8^b which are connected by the leads 9, 9^a, 9^b with the primary coil PC (Figs. 1 and 3). The clips 8, 8^a, 8^b are mounted on cross piece 60. The outer end of the primary coil PC is connected to one end of the spark gap by a lead 72. The opposite end of the spark gap SG is connected by a lead 73 to the case side of the condenser, completing the primary circuit P. A lead 72^a also connects coil PC to 15 the condenser C for the longest wave length 20 adjustment.

One of the magnetic controls I, II, III, IV for actuating the switch arms 63 is illustrated in Figs. 6, 7, 8, the controls being 25 mounted on the front of middle panel 22 of Fig. 2. Each control comprises a plunger 74 having an end 75 pivotally connected to the lower end of arm 63 and slidably mounted in the casing 65 and extending through 30 panel 22 to the front. Fixed to the plunger 74 between its end 75 and casing 65 is an abutment ring or collar 76 between which and the casing 65 is mounted a spring 77. A handle 78 is secured to the opposite end 35 of plunger 74 in front of the transmitter. When the handle 78 is pulled out, as indicated in full lines, Fig. 6, spring 77 is compressed and the arm 63 is moved to close the switch contacts. To lock the plunger 74 in 40 operative position, a plunger pawl 79 is forced into a recess or slot 80 in the rod 74 by means of spring 81 as the plunger is pulled back. A lever 82 pivoted at 83 to the casing 65^a is also pivotally connected at 45 84 to the outer end of the pawl 79, the spring 81 being interposed between lever 82 and the casing 65^a surrounding the locking device 79. When the lever 82 is depressed by hand, it raises the pawl 79 out of locking 50 engagement with the plunger or rod 74, allowing the compressed spring 77 to force the rod 74 inwardly to swing the arm 63 to inoperative or normal position. The lever 82 and locking mechanism is mounted in 55 front of the panel 22 where it is accessible.

When the wave-changer contacts are fully 60 engaged, the plunger 74 is stopped by a brass washer 85 and a tubular shouldering piece 86 which is fixed relative to the plunger 74. In the open switch position of the

system, the device is stopped by a stop or abutment 87 secured to the slide rod 4 (Fig. 3) and adapted to engage the crosspiece 61. A quarter-inch hammer action is provided between the plunger 74 and arm 63. This is 70 secured by providing a hole 88 in the end 75 of plunger 74. The arm 63 is connected to the plunger 74 by means of a pin 89 riding loosely in the hole 88. The hole 88 is off center relatively to the axis of the plunger, 75 being located more below the axis than above it. The co-ordination of bumpers, stops, pawl and spring assures the presence of the hammer blow at the beginning of both the opening and closing action of the system to 80 overcome the static friction.

The system can also be electromagnetically or electrically operated for control from a distant point, alternative with operation of handle 78. Around the plunger 74 is coil 85 90 enclosed in the casing 65. If the coil 90 is excited or energized, the plunger 74 is drawn outwardly against the spring force 77 and the friction of the system. When the plunger 74 reaches the stop 85, the pawl 79, which rides over an enlarged portion of the plunger 74, locks the latter, dropping into recess 80 by reason of the spring 81. The plunger 74 is in three parts,—right-hand part 74^a (Fig. 6) of enlarged cross 95 section, an intermediate part 74^b of reduced cross section in which the slot 80 is located, and sliding in the piece 86, and an outer part 74^c threaded onto the intermediate part and guided in the piece 86. The inner end 100 of part 74^c forms one shoulder of recess 80 and the pawl 79 rides past 74^c when the plunger is moving into and from operative position. Upon the downward movement 105 of the pawl 79, an insulating button 91 on the inner end of the lever 82 likewise moves downward, allowing a pair of contacts 92 to open, the contacts 92 controlling the circuit of the electromagnetic coil 90. The contacts 92, shown in Figs. 2, 6 and 8 and 110 diagrammatically in Fig. 1, comprise a pair of transversely-arranged springs secured at their outer ends and overlapping at their inner ends and provided with contacts, these springs normally being arranged to be out 115 of engagement with each other except when moved into engagement or contact by the upward movement of the button 91. In each instance, as soon as the pawl 79 locks the plunger 74, the circuit through the coil 90 120 is broken upon the separation of the contacts 92 so that such coils 90 are only energized during the period of useful work or during the movement of the plunger. Attached to the casing or shell 65 in front of 125 the collar 76 is a pair of similar leaf spring contacts 93 overlapping at their inner ends, secured at their outer ends to and insulated from the casing 65 and normally arranged to be out of engagement with each other. Con- 130

facts 93 are shown in Figs. 6, 7 and 8 and diagrammatically in Fig. 1. Upon the outward movement of the plunger 74, an insulating button 94, attached to the collar or abutment 76, engages the spring contacts 93, closing a circuit including a magnetic coil 95 surrounding the pawl plunger 79. It will thus be seen that when the plunger 74 moves outwardly to operative position shown in 10 full lines in Fig. 6, the contacts 93 controlling the coil 95 surrounding the pawl are closed, placing such circuit in a condition to be energized (by means to be described) in order to move the pawl 79 out of engagement with the plunger 74, allowing the spring 77 to move the plunger or mechanism to inoperative position. The movement of the plunger 74 to inoperative position opens the contacts 93 deenergizing the 20 pawl coil 95. Obviously the plunger portion 74^a and pawl 79 must be of magnetic material such as steel or iron. The system employed is one in which the magnet coils 90, 95 are energized only during the period 25 of their useful work and are automatically cut out of the circuit as soon as this useful work has been completed.

A condenser 96 is placed across the contacts 92 to quench any tendency of arcing. 30 The contacts 92 and 93 may be of tungsten. The intermediate part 74^b of the plunger 74 is of Monel metal to prevent short-circuiting of the useful flux of the magnets, while the outer part 74^a is of steel to provide a hardened ledge for the returned shock of such strength that the material will not be damaged and to reduce friction to a minimum.

All four pairs of magnet systems 90, 95 are rigidly locked to a steel plate 97 which 40 is firmly fastened to the angle iron framework 20 of the transmitter, openings being provided in the panel 22 to allow the handles 78 and the pawl mechanisms 82 to be at the front. The construction provides inter-changeability, perfect alinement of moving parts, and reduces the shock of the system to a negligible value. The system runs freely if properly oiled.

Each magnetic system may be disassembled by disconnecting the arm 63 from the rod 4-11, plunger 74 and bracket 64 and removing it. Remove handle 78 and collar 76. Pull the plunger 74 to the right enough to remove the set screw 98 and unscrew part 55 74^a from part 74^b and remove the parts. To replace the main magnet coil 90, remove the screws 99 securing the casing 65 to the plate 97. The detent magnet 95 may be removed by first removing nut 100 at the front. The 60 detent magnet casing 65^a can then be withdrawn from the mounting rod 86. The main magnet coil 90 is mounted on a brass tubing 102, the coil being built around it. This tubing telescopes in the rear through the 65 casing 65 and at the front extends around

the stop 86. Detent magnet coil 95 is likewise built on a brass tubing 103. Lever arm 82 may be removed by loosening the screws constituting its pivot 83. The casing 65^a for the detent magnet 94 has a removable cover 104. The parts may be reassembled in the reverse order.

It has been found by actual experience that rather large forces are required to perform the operating cycle for each electromagnet system. For example, a force of approximately sixteen pounds along the plunger 74 is necessary to move the system. The magnet for operating the plunger 74 has been designed for an initial force of 80 twenty-three pounds. The spring 77 in a constructed embodiment of the invention was designed with an initial force of five pounds. In its closed or compressed position, the spring 77 has a force in the neighborhood of 85 twenty-five pounds. The system is quite rapid inasmuch as there is no residual magnetism to hold the plungers 74-79 in the solenoids when a change is desired, since the 90 operation cuts off the current from the solenoid to be operated. The magnet coil control contacts 92-93 are required to make and break circuits carrying currents in the neighborhood of three amperes, and successfully do this especially when a condenser is connected across the contacts.

The means or circuits for operating the several electromagnetic devices from a distance to make the various adjustments is illustrated diagrammatically in Fig. 1, the 100 operator's distant wave length control being shown diagrammatically at OC. The line LL represents a source of direct current. One side *l* of the line LL is connected to a movable switch contact *m*. The other side 105 of the line LL is connected to a terminal of each magnet 90, 95 respectively of the devices I, II, III, IV. If the common movable switch or contact arm *m* is moved into engagement with the terminal *a*, it closes the 110 circuit through any detent magnet coil 95 in which its contacts 93 are closed, as device II, Fig. 1. This releases the plunger 74 by raising the detent 79. After this is done, if the contact arm *m* is swung to engage any desired contact, *c*, *d* or *e*, a circuit is closed through the desired plunger-actuating magnet 90, the contact *c* being electrically connected to the coil 90 of system I, the contact *d* being electrically connected to the coil 90 120 of system II and the contact *e* being electrically connected to the coil 90 of system III. The circuits *c*, *d*, *e*, including line LL have each interposed in them the contacts 92 above described.

System IV for the send-receive device is controlled by the send-receive switch SR. The movable member of the switch SR is electrically connected to the side L of line LL, the other side of the line LL being con- 130

nected to a terminal of the coil 90 and to a terminal of coil 95 respectively of device IV. When the send-receive switch SR is moved to a position in engagement with the contact P, it closes a circuit through the coil 95 and closes contacts 93 for the purpose of raising its detent and throwing the plunger 11 from the transmitting position on control 13 shown to receiving position on control 14. When the switch SR is moved into engagement with the contact O, system IV being in receiving position, the coil 90 of that system will be energized to draw back its plunger 74 and changing to the transmitting position, contacts 92 being now closed.

Having described a general scheme of controlling the several electromagnetic devices from a distance as illustrated in Fig. 1, a control panel OC, Figs. 9 and 10 will now be described. This distant control device OC consists of a metal panel 105 adapted for desk mounting, upon which is mounted a small transmitting key 106 for operating the relay key on the transmitter and a large transmitting key 107 for operating the transmitter directly. On the panel are mounted the send-receive buttons 108 (Fig. 9) controlling the switch 109 (Fig. 10) for controlling send-receive device IV at the transmitter.

The mechanism 110 on control panel 105 of Figs. 9-10 will now be described. At the rear of the panel (Fig. 10) is secured a vertically-arranged insulating board 111 having ten external terminals 112 mounted thereon. Eight of these terminals are in low current control circuits connected to the distant transmitter for controlling the wave-changer devices, relay key and send-receive device of Figs. 1-3. Two of these terminals are for heavy leads in circuit with the key 107 and connected to corresponding terminals on the transmitter of Figs. 1-2. Two terminals 113 in addition to the above ten connect to the detector binding posts, and are for the purpose of short-circuiting the detector during transmission. This short-circuiting is accomplished by the send-receive switch 108, 109. Across the small key 106 is placed a condenser. The live parts mounted below the panel 105 are enclosed in a container 114.

The control panel 105 has four openings 115 arranged on an arc of a circle and corresponding to the four wave-length adjustments for which the transmitter illustrated is adapted. The number of wave-length adjustments, however, may be increased or decreased from the number shown. These four openings 115 are marked to designate the corresponding wave-lengths, as here illustrated, 300, 600, 800, 1800 meters. Mounted below each opening 115 are spring contacts 116 (Fig. 10). These contacts are arranged to be closed when the control handle 117 is

placed in any of the openings 115. The handle 117 is swivelled by means of a bolt 118 to one end of a channel-shaped arm 119 universally pivoted to allow the handle 117 to be raised out of each hole 115 and to be swung to and into any other hole, the bolt 118 terminating at its lower end in an insulating button 120 adapted to engage and close the contacts 116 (corresponding to contacts c, d, e, Fig. 1).

To allow the universal movement of the lever or arm 119, the panel 105, at a point constituting the center of the arc on which the holes 115 are arranged, is provided with a bearing opening 121. Rotatably mounted in this opening is a tubular member 122 having a pair of ears 123 at its upper end. The arm 119 straddles these ears and is pivoted thereto by means of a pin 124.

Slidably mounted through member 122 is a pin or plunger 125. Surrounding the plunger 125 is a spring 126 within the member 122 and held in place by a cap 127. The spring 126 tends to maintain the plunger in elevated position, engaging an abutment 128 secured thereto. The lower end of plunger 125 below cap 127 has an insulating head 129 which when depressed engages and closes a pair of spring contacts 130 (corresponding to contacts A, M, Fig. 1).

A spring washer 131 is interposed between the cap 127 and the bearing of the panel to provide frictional resistance to the rotation of the member 122. The plunger 125 is depressed when the handle 117 is lifted out of a hole 115. For this purpose, a bar 132 is pivoted at a point 133 between its ends to the ears 123, extending at one end between the upper end of plunger 125 and pin 124 and extending at its opposite end over a cross pin 134 secured to arm 119.

The upper one of each set of contacts 116 is electrically connected to binding posts 135 which are electrically connected together by a strip 136 and have a common external binding post 112^a. The lower of contacts 116 are separately mounted on panel 111 and electrically connected to external binding posts 112^b. The contacts 130 are mounted on an insulating panel 137, the upper one being electrically connected to a binding post 138 on panel 137 and post 138 being connected by a conductor 139 to one of the posts 135. The lower contact 130 is electrically connected to a conducting rod 140 mounted in panels 111-137 and forming an external binding post 112^c. The upper contacts 116, 130, one terminal of the send-receive switch 108 and one terminal of key 106 are connected to binding post 112^a. The other terminals of the send-receive switch 108 are connected to the external binding posts 112^b and the other terminal of the small key 106 is connected to binding post 112^c. The large key 107 is connected to external binding 138

posts 112^c (Fig. 9). The binding posts 112^c are connected to the detector for short circuiting the detector from the switch 109. External wiring is provided to the necessary elements on the transmitter and to the source of direct current for operating the send-receive switch IV, wave changers I, II, III and relay key 32. When the handle 117 is raised to disengage a pair of contacts 116 below an opening 115, the movement of arm 119 around its pivot 124 will raise the end of bar 132 above pin 134, the rear end of the bar depressing the plunger 125, closing the contacts 130. When contacts 130 are closed, any electromagnetic device I, II, III which is in operative position is opened, throwing the transmitter into the fourth or longest wave-length position. The handle 117 can then be moved to any other of the wave-length openings 115 to secure any desired wave-length adjustment. When the handle 117 is placed in another opening 115, another wave-length adjustment is secured and the contacts 130 are opened.

The actuation of the operator's wave-length control 117 ensures that all the electromagnetic devices I, II, III of the transmitter must be first opened before a new wave-length adjustment can be thrown in. These several adjustments may be secured by a single movement of the control handle to different positions, the longest wave-length adjustment requiring no operation of electromagnetic control devices. The wave length opening 115 marked 1800, therefore requires no switch contacts therein, and is merely a dead hole to indicate the longest wave-length position.

In Figs. 4 and 5 is illustrated a structural embodiment of the switches for the local circuits controlled by the send-receive control IV and illustrated diagrammatically in Fig. 1. The several switches 16, 17, 18 and 19 are secured to an insulating base 145, in turn secured to the rear of the middle panel 22 (Fig. 3) at a point in line with rod 11 of device IV. Each switch is mounted on angle brackets 146 secured to base 145 and having terminals 147 for connection to the circuits controlled by the switches. The switch 19 comprises a pair of metal arms 148 secured flexibly to brackets 146 by means of leaf springs 149 secured to their sides and to the brackets. Leaf springs 150 are likewise secured to the brackets 146 and engage the opposite sides of arms 148 to maintain spring pressure on them when displaced or separated. The arms 148 diverge at their outer ends 151. Secured to one arm 148 is a metal loop 152 which extends around the other arm and is provided with a contact 153 normally out of engagement with the arm but adapted to contact therewith when the arms are separated. The switches 16, 17 and 18 comprise also metal arms 154 which are flexibly connected to their brackets by leaf springs 149 and have contacts 155 secured to their inner sides. Leaf springs 150 bear against the opposite sides of the arms 154 to maintain the contacts 155 in engagement to close the circuits controlled by the switches. The arms 154 likewise diverge at their outer ends 156, but are shorter than the arms 148. The several switches are actuated by an insulating wedge plunger 11^a secured to the forward end of rod 11. The plunger 11^a has a metal pin 151^a adapted to enter between the arms 148, closing the circuit across them. The plunger 11^a after the circuit of switch 19 is closed, enters between the arms 154 opening the circuits controlled by them. Upon the withdrawal of the plunger 11^a, circuits 16, 17 and 18 are closed and circuit 19 opened. The transmitter is then in the transmitting position. The circuits controlled by switches 16, 17, 18, 19 were mentioned above. The switches 16-19 are illustrated in Fig. 3, the plunger 11 being slidably supported in crosspieces 60-61. (The transmitter is in receiving position with the plunger 11^a engaging the contacts.) The contact blade 12, which is connected to the antenna through lead A², is disconnected from blade 13 on panel 36 and is connected to blade 14 mounted on piece 61 and connecting the aerial to the receiver. These parts are not seen in Fig. 3, but their arrangement is shown in Fig. 1.

Directly behind the top panel 23 (Fig. 3) is located the antenna load coil system L, the system consisting of seven concentric pancake coils 3, 3^a, 3^b, etc., whose axis is perpendicular to the axis of the primary and secondary coils PC, SC. The four lowest coils have variometer attachments with manual controls 157 projecting through the front of the top panel. The lowest variometer is the only portion of the antenna load coil system in circuit on the shortest wave length. Continuous tuning control of the shortest wave length is provided by the lowest variometer handle 157 on the front of the panel. The next longest wave length has in circuit a portion of either the whole or half of the lowest variometer coil and the variable portion of coil 3^a. Tuning control for this wave length is provided by the second variometer handle 157. The next longest wave length has in circuit portions of the two lowest variometer coils and the variable portion of coil 3^b. The wave length is tuned by the third variometer handle 157 from the bottom. The longest wave length has in series portions of the three lowest coils, a variable portion of the fourth lowest coil, and portions of the three top coils. This wave length is controlled by the top variometer handle 157. The coils are separated by fixed insulating tubular spacers 130.

- 158 which provide alinement for the variometer shaft handles and determine the voltage safety factor between successive coils. When the set has been tuned for the 5 several wave-length adjustments, the variometers 157 may be independently locked by means of the locking devices 159 to the right of the variometer shafts on the front of the panel 23.
- 10 The mounting for the coils 3, 3^a, 3^b, etc., comprises lower insulating blocks 160 mounted on tubes 37 and in which are secured vertical insulating shafts 161. Threaded on shafts 161 are the insulating spider frames 15 162 supporting the coils, the tubular spacers 158 being interposed between the successive spider frames upon rods 161, providing a high value of air insulation and leakage insulation to ground and to points on the set.
- 15 On the lower portion of the front center panel 22 (Figs. 2 and 3) are located a quenched gap rack 163 and quenched gap switch 164. The quenched gap is the self-cooled type. The gap comprises twelve units 20 165 mounted in the rack. Full power can be obtained with eleven units in the circuit. The rack contains spring members 166 which provide sufficient clamping for holding the units in the rack on their guides and which 25 will close the gap circuit, should one of the units be removed. The entire gap is placed across the transformer T (Fig. 1). This prevents the possibility of potential exceeding the value limited by twelve series gaps. The 30 gap switch 164 is arranged so that it successively cuts in more units 165 as the switch 35 is moved to the right facing the panel. It functions to short-circuit gaps to its right.
- Upon the upper panel 23 (Fig. 2) are 40 mounted the meters 167, the variometer controls 157 and four push button switches 168. There are three meters. One is a double scale voltmeter for reading the D. C. voltage or the generator voltage. One of the push 45 button switches 168 mounted below the voltmeter permits the choice of A. C. or D. C. reading. The radiation ammeter is of the usual thermo element type and accurate over the range of 300 to 2000 meters. The wattmeter is calibrated for 500 cycles. All meters 50 possess a high damping and have calibration accuracy of plus or minus two per cent with the currents, voltages and powers on which they function in the transmitter. One of the push button switches 168 gives the operator 55 the choice of either stopping the motor generator each time the send-receive switch is thrown or permits him to keep the motor generator running when the antenna switch 60 is in the receiving position. Another switch 168 controls the key circuit and gives the operator the choice of operating the transmitter by either the hand key or the relay key, which are located on the control unit. The 65 other push button switch 168 functions to

cut in an additional fixed resistance in series with the generator rheostat so as to permit a further decrease of generator voltage over the voltage range permitted by the rheostat alone. This resistance is of such value that 70 an overlap is obtainable in going from the highest resistance in the rheostat to the fixed resistance and the lowest resistance in the rheostat, in effect, providing for a continuous variation in voltage from the voltage 75 for full power to the voltage necessary for 60-watt operation.

The transmitter herein illustrated, to which the control system of the present invention is applied, is of the musical quenched 80 spark, a thousand sparks per second type. The transmitter has a wave-length range of 300 to 2000 meters on antennæ of capacity .0008 mfds. to .0016 mfds. The transmitter may be adjusted to any four-wave lengths 85 in this range. The power rating of the transmitter is based upon the input into the primary radio frequency circuit.

The present invention, however, is applicable to other types of transmitters. Where 90 tube transmitting systems are employed, very much lighter mechanical systems can be employed for changing the wave lengths. For example, in a tube transmitter system in which the wave length is obtained by a master 95 oscillator tube oscillating at radio frequencies and with the radio frequency impulses impressed on an untuned amplifier bank of power tubes, the wave length may be changed 100 by a light contact system regulating the oscillator tube.

For arc transmitters, various solenoid or 105 motor-driven devices controlled from a distance as above described may be employed to strike the arc and to vary its length and to control contacts, etc., controlling devices such as the cooling pump and the carbon 110 rotating motor. Distance controls of the character above described may also be used to control the radio frequency and power circuits of a high frequency alternator.

I have thus described a highly efficient 115 type of control system changer which may be operated at a distance to control the various adjustments, these adjustments being secured individually for each adjustment by means of electromagnetic controls, although 120 motors or other suitable instrumentalities may be employed. The magnets, however, are energized only during the time of useful work, and are automatically cut off at the end of that time. These devices are controlled electromagnetically in one direction, and by a spring in the opposite direction.

Each wave-length adjustment is secured 125 by closing one contact in the primary circuit and one contact in the antenna circuit, thereby reducing the number of contacts to a minimum. The longest wave-length adjustment in this system is secured by a short- 130

circuiting clip Y (Fig. 1) connecting the antenna coil system L and the secondary coil SC directly, and closing the primary coil PC directly through the common lead 5 of the primary coil system. The system is tuned to the longest wave length when all of the wave-changer switches are open. An advantage, aside from the saving of a wave-changer device for the longest wave length 10 is that both the primary and secondary circuits are thereby connected in tuned relation on the open position of all the wave-changer switches. Therefore, if an operator operates his wave-changer while the key is depressed, 15 no harmful effect is produced, inasmuch as the interim between the opening of one set of contacts and the closing of another set of contacts for the shorter wave lengths is covered by the transmitter functioning on a 20 tuned position, thus effectually preventing a rise in potential of either the primary or secondary systems above operating potentials.

In this wave-changer, the antenna lead 25 is swung directly from the transmitter to the receiver, the receiver antenna post being located on the transmitter and being connected to ground when the antenna lead is on the transmitting connection. This 30 ground is removed by the entrance of the antenna blade 12 (Fig. 1) into the receiver clip 14. By grounding the receiver during transmitting, the capacity effect is minimized. In the first, second and third coils 35 from the bottom, the variometer arms connect directly to the switch clips 1, 1^a, 1^b of the wave-changers. In the fourth coil from the bottom, the variometer is in series with the outer end of the fifth coil from the 40 bottom, and the outer end of the fourth coil from the bottom is in series with the inner end of the third coil from the bottom. This connection permits the use of a fixed short-circuit lead Y for the longest wave-length, 45 and also provides a variometer adjustment in this wave length.

I claim:

1. The combination with a radio transmitter including a circuit to be controlled, of 50 a panel on the back of which are supported parts of said transmitter; a switch for said circuit mounted on the rear of said panel; a plunger-casing mounted on the panel; a plunger extending thru the panel and connected to operate said transmitter switch; a spring holding the plunger in one of its 55 positions, and a lock holding it in another of its positions.

2. The combination with a radio transmitter including a circuit to be controlled, 60 of a switch for such transmitter circuit; an electromagnetically operated member connected to operate said transmitter circuit switch; a locking member holding said 65 switch operating member in the position to

which it has been moved by its magnet to operate said transmitter circuit switch; a master switch for said electromagnet and located more or less remote therefrom; a second switch in the circuit of the electromagnet of said switch operating member; means carried by said switch operating member and opening said second switch after the locking member reaches its position holding 70 said switch operating member; means restoring said switch operating member, said second switch, and said transmitter circuit switch to their initial positions, wherein the master switch is operative on the electromagnet of said switch operating member; 80 and means moving said locking member from its said locking position and permitting operation of said restoring means.

3. The combination with a radio transmitter including a circuit to be controlled, 85 of a switch for said circuit; a member connected to operate said transmitter circuit switch; means operating said switch operating member to operate said switch; a locking member holding said switch in the position to 90 which it has been moved to operate said transmitter circuit switch; means restoring said switch operating member and switch to their initial positions; an electromagnet removing said locking member from its locking 95 position and permitting the operation of said restoring means; a master switch for said electromagnet and located more or less remote therefrom; a second switch for the circuit of said electromagnet; and means operated by movement of said transmitter switch operating member toward its locked position and closing said second switch, thereby putting said electromagnet circuit 100 and locking member in condition to be operated by said master switch and permit operation of said restoring means.

4. The combination with a radio transmitter including a circuit to be controlled, of 110 a switch for said circuit; an electromagnetically operated member connected to operate said switch; a locking member holding said switch in said operated position; means moving said locking member into such locking position; means restoring said switch operating member and transmitter circuit switch to their initial positions; an electromagnet moving said locking member from its locking position, permitting operation of 115 said restoring means; master switching means controlling both said electromagnets, and located more or less remote therefrom; a second switch in the circuit of the electromagnet of said transmitter circuit switch operating member and means carried by said locking member and opening said second switch after the locking member reaches its locking position; and a second switch in 120 the circuit of the electromagnet of said locking member and means carried by the switch 125

130

operating member and closing said second switch after the locking member is in locking position; all whereby the operation of the transmitter circuit switch is controlled by said master switching means, and said electromagnets are energized only while moving the switch operating member and locking member respectively.

5. The combination with a radio transmitter including a circuit to be controlled, of a switch for said circuit; an operating member for said switch; a lock for said switch; an operating means for said lock; manually operating means operating said switch operating member and lock operating means; electromagnetic means operating said switch operating member and lock operating member alternatively with said manually operating means at will; and master switching means more or less remote from said electromagnetic means and operating members, and controlling said electromagnetic means, all whereby the operating movements and locking of said transmitter circuit switch are controlled by said master switching means.

6. The combination with a radio transmitter including a circuit to be controlled, of a switch for such circuit; a spring; an electromagnet operating said switch and also said spring to place the latter in condition to restore the former to its initial position; a lock holding said switch in the position in which it is moved by said electromagnet; an electromagnet disengaging said lock and permitting restoration of said switch by said spring; and master switching means controlling both said electromagnets and located more or less remote therefrom.

7. The combination with a radio transmitter including a circuit to be controlled, of a switch for said circuit; an operating member for said switch; a lock for said operating member; and means for operating said operating member and said lock.

8. The combination with a radio transmitter including a plurality of circuits changing the wave length thereof, of a plurality of wave changing switches controlling said circuits; a plurality of electromagnetic devices operating said switches; and master switching means controlling said electromagnetic devices and located more or less remote therefrom; each electromagnetic switch and the master switching means being co-operatively constructed to cause restoration of each switch from its operated position by the master switching means prior to the operation of any other of said electromagnetic switches by the master switching means.

9. The combination with a radio transmitter tuned normally to a given wave length and including a plurality of circuits changing to different wave lengths from said normal wave length; of a plurality of wave

changing switches controlling said circuits; a plurality of electromagnetic devices operating said switches; and master switching means controlling said electromagnetic devices and located more or less remote therefrom; each electromagnetic switch and the master switching means being co-operatively constructed to permit restoration of each switch from its operated position prior to the operation of any other of said electromagnetic switches; and the transmitter preserving its said normal wave length between operations of said successive switches and at all times when none of said switches is in its operated position, thereby preventing undesirable rise of potential during intervals between wave length adjustments.

10. The combination with a radio transmitter including a plurality of circuits changing the wave length thereof, of a plurality of wave changing switches controlling said circuits; a plurality of electromagnetic devices operating said switches; and master switching means controlling said electromagnetic devices and located more or less remote therefrom; each of said switches being provided with means locking it in its operative position and open-circuiting its electromagnet when in its locked position.

11. The combination with a radio transmitter comprising an aerial including loading coils and an adjustable secondary inductance coil; of a plurality of wave changing switches each controlling said secondary and loading coils; a plurality of electromagnetic devices operating said switches; a connection between said secondary inductance coil and said loading coils which connection is normally maintained; and a master switching means controlling said electromagnetic devices and located more or less remote therefrom.

12. The combination with a radio transmitter and receiver, of a send-receive switch, said transmitter including a plurality of wave-changing circuits; a plurality of switches controlling said wave changing circuits; a plurality of electromagnetic devices operating said send-receive switch and said wave changing switches; and master switching means respectively controlling the electromagnetic devices operating said send-receive switch and the electromagnetic devices operating said wave changing switches; said master switching means both being located in the same vicinity and more or less remote from said electromagnetic devices.

13. The combination with a radio transmitter and receiver and a common aerial for said transmitter and receiver, of a send-receive switch by which the receiver is grounded while the transmitter is operatively connected to said aerial; an electromagnetic device operating said switch; means for locking the switch in its position

- connecting the transmitter to the aerial, a master switch controlling said electromagnetic device and located more or less remote therefrom; means controlled by said locking device for open-circuiting said electromagnetic device; and means independent of the electromagnet of said device for restoring said switch to its initial position when released from said locking device.
14. The combination with a radio transmitter including a secondary coil, and a plurality of circuits changing its wave length, of a plurality of wave-changing switches controlling said circuits; a plurality of electromagnetic devices operating said switches; and an antenna-shortening condenser connected between the transmitter secondary coil and the switch effecting change to the shortest wave length; and master switching means controlling said electromagnetic devices and located more or less remotely therefrom.
15. The combination with a radio transmitter comprising aerial including loading coils and an adjustable secondary inductance coil, of a plurality of wave changing switches controlling said coils; a plurality of electromagnetic devices operating said switches; a connection between said secondary coil and said loading coils which is normally maintained; an antenna-shortening condenser connected between the transmitter secondary coil and the switch effecting the change to the shortest wave length; and master switching means controlling said electromagnetic devices and located more or less remotely therefrom.
16. The combination with a radio transmitter including a circuit to be controlled, of a switch controlling said circuit, an electromagnetic device operating said switch; a lock holding said switch in its operated position; an electromagnetic device disengaging said lock from said switch; means operated by the lock to open-circuit the electromagnet of said switch, means operated by the switch to close the circuit of the electromagnet of the lock, and a master switch constructed to open-circuit the electromagnet of the switch in one movement of the master switch, and to close the circuit of the electromagnet of the lock in another movement of the master switch.
17. The combination with a radio transmitter having a permanent normal wave length, of a plurality of circuits changing such wave length to other values; a plurality of switches controlling said circuits; a plurality of electromagnetic devices operating said switches; and a master switch controlling said electromagnetic devices, said master switch and said electromagnetic switches being co-operatively constructed to open one switch before closing another, and the transmitter resuming its permanent normal wave length in the interval between the opening of one of said switches and the closing of another.
18. The combination with a radio transmitter including a plurality of circuits changing the wave length thereof and a plurality of other transmitter operating circuits, of a plurality of switches controlling said wave changing and operating circuits; a plurality of electromagnetic devices operating said switches; a master switch controlling a plurality of said electromagnetic wave changing switches; and a second master switch controlling said electromagnetic switches for said operating circuits; said master switches being located in the same vicinity and more or less remote from said electromagnetic devices.

WILLIAM H. PRIESS.
